G. S. WILKINSON

CYLINDER FOR INTERNAL COMBUSTION ENGINES

Filed Dec. 29, 1922

FIG. I.

FIG. 2.

FIG. 3.

G. S. Wilkinson, ^{INVENTOR.}

Watson, Cott, Morse & Grindle,
Attys

UNITED STATES PATENT OFFICE.

GEORGE SHAKESPEARE WILKINSON, OF LONDON, ENGLAND, ASSIGNOR TO D. NAPIER & SON LIMITED, OF LONDON, ENGLAND, A COMPANY OF GREAT BRITAIN.

CYLINDER FOR INTERNAL-COMBUSTION ENGINES.

Application filed December 29, 1922. Serial No. 609,738.

To all whom it may concern:

Be it known that I, GEORGE SHAKESPEARE WILKINSON, a subject of the King of England, and residing at London, in England, ⁵ have invented certain new and useful Improvements in Cylinders for Internal-Combustion Engines, of which the following is a specification.

The invention relates to cylinders for internal combustion engines more particularly air-cooled cylinders of that type in which an open-ended cylinder formed of steel or similar metal has mounted on its end a head constructed of aluminium or aluminium ¹⁰ alloy and has for its object to effect certain improvements in the juncture between the head and the cylinder.

In air-cooled cylinders of the type in question owing to the different coefficients of ²⁰ expansion of the metals of which the cylinder and head are formed, there is a difficulty in maintaining a tight joint between these parts and the present invention is directed to providing a construction of such a nature that a tight joint will be ensured while, if desired, the construction will permit of the head being readily detached.

According to this invention a head formed of metal having a coefficient of expansion ³⁰ different from that of the metal of which the open-ended cylinder is formed is screwed or otherwise mounted on the cylinder so as to enclose the end of the latter. A ring formed of a metal which is either the same as that of the cylinder or has a similar or ³⁵ greater coefficient of expansion is mounted and fits closely on that part of the head which surrounds the end of the cylinder. Thus that portion of the head which engages the end of the cylinder lies between the cylinder and the separate ring, the latter being screwed or otherwise fixed on to the head. The head may thus be provided with an annular flange internally screw-⁴⁰ threaded to engage the correspondingly screwthreaded end of the cylinder. The ring which fits closely on and around the head flange is constructed, together with this flange, so that the engaging portions of these ⁴⁵ members are either plain or wholly or partially coned and screwthreaded. In this way the flange or corresponding portion of the head which surrounds the end of the cylinder is so engaged by the separate ring as ⁵⁰ to be clamped by this ring on to the end of

the cylinder and in this way a tight joint is maintained between the head and the cylinder since the cylinder and the ring will expand equally.

The invention may be carried out in practice in various ways but the following may be instanced as alternative constructions that may be adopted.

In each case the cylinder A, which is preferably formed of steel, carries radiating ⁶⁵ fins A' except at or near its upper end, the cylinder being formed with both ends open. The exterior of the upper or outer end of the cylinder is screwthreaded as at A² and on to the cylinder is screwed the head B ⁷⁰ which may be made of aluminium or aluminium alloy and is given a suitable structure with external radiating fins B'. The part of the cylinder head which screws on to and engages the end of the cylinder is in ⁷⁵ effect an annular flange B² but this part may be constructed in various ways as found desirable.

In the accompanying drawings,

Figure 1 shows in vertical section one ⁸⁰ form of cylinder head and locking ring according to this invention, and

Figures 2 and 3 show also in vertical section modified forms of locking ring and that portion of the cylinder head with which ⁸⁵ they cooperate.

In the arrangement shown in Figure 1 the locking of the head B on the cylinder A is effected as follows. The exterior of the head flange B² which engages the end of the cylinder is formed conical at its upper end C but for its remaining length it is formed parallel to the cylinder and screwthreaded as at C'. A ring D constructed for example of the same steel as the cylinder and conveniently provided on its exterior with radiating fins D' is internally coned and screwthreaded to engage the exterior of the head flange B². When this ring is in position and screwed up, the flange B² will be ⁹⁰ clamped or held between the ring D and the cylinder, and since both these parts are formed of metal or metals having the same or substantially the same coefficient of expansion the expansion of the interposed metal of the head will be controlled and a tight joint between the head and the cylinder maintained.

In an alternative arrangement shown in Figures 2 and 3 the exterior of the head ¹⁰⁰ 110

flange is coned throughout its length and screwthreaded over its centre part as at E in Figure 2 or at its upper end as at F in Figure 3. In each case the interior of the 5 clamping ring is formed to correspond with the exterior of the head flange. The angle of the conicity of the exterior of the head flange either in this case or in the arrangement described above may vary as found desirable.

Yet again the exterior of the head flange may be smooth and parallel with the interior of the cylinder, the clamping ring being pressed or shrunk into place on the head 15 flange.

Other arrangements may be adopted if desired but in each instance it is to be noted that the locking or clamping ring is carried entirely on the flange or other part of the 20 head which engages and encloses the end of the cylinder so that the ring is not in contact with the cylinder and the metal of the head flange is disposed and held between the wall of the cylinder and the interior of the ring.

Sufficient clearance is left between the end 25 of the head flange and the adjacent radiating rib or ribs on the cylinder so as to facilitate the placing of the ring in position or its removal if it is desired to detach the head 30 from the cylinder.

As mentioned above, the separate ring 35 may be formed of a metal which is the same as or similar to that of which the cylinder itself is formed. In some cases, however, in place of the ring metal being such as to have the same or approximately the same coefficient of expansion as the cylinder metal, there may be employed in the structure of the ring a metal which has a greater coefficient of expansion than the cylinder metal. 40 This may be desirable in view of the cylinder being subjected to a higher temperature than the outer ring. It is also desirable to determine the expansion of the ring with relation to the thickness of the metal in the 45 head flange which is interposed between the ring and the cylinder. In any case it is the object of the invention to constrain the head flange between concentric metal annuli, 50 namely, the end of the cylinder and the ring these annuli being formed so that they will expand in a substantially similar manner and thus counteract the tendency of the head flange to expand away from and thus 55 break the joint with the end of the cylinder.

The details of constructions may be modified as found desirable.

What I claim as my invention and desire to secure by Letters Patent is:—

60 1. In an air-cooled cylinder for internal combustion engines the combination of an open-ended cylinder threaded externally at one end, a cylinder head screwed on to the threaded end of the cylinder and formed of a metal having a coefficient of expansion

different from that of the metal of which the cylinder is formed, and an annular member mounted wholly on and fitting closely on that part of the cylinder head which lies around the end of the cylinder spaced from 70 the cylinder and formed of a metal having substantially the same coefficient of expansion as that of which the cylinder is formed.

2. In an air-cooled cylinder for internal combustion engines, the combination of an 75 open-ended cylinder, a cylinder head fitting on to and enclosing one end of the cylinder and formed of a metal having a coefficient of expansion different from that of the metal of which the cylinder is formed, and an annular member screwed on to that part of the cylinder head which lies around the end of the cylinder completely spaced from the cylinder and formed of a metal having substantially the same coefficient of expansion as that of which the cylinder is formed.

3. In an air-cooled cylinder for internal combustion engines, the combination of an 80 open-ended cylinder, a cylinder head fitting on to and enclosing one end of the cylinder and having a coned surface formed on that part of the head which lies around the end of the cylinder, the cylinder head being formed of a metal having a coefficient of expansion different from that of the metal of which the cylinder is formed, and an annular member wholly mounted and fitting closely on the coned portion of the cylinder head spaced thereby from the cylinder and formed of a metal having substantially the 85 same coefficient of expansion as that of which the cylinder is formed.

4. In an air-cooled cylinder for internal combustion engines, the combination of an 90 open-ended cylinder, a cylinder head screwed on to one end of the cylinder and having a coned surface formed on that part of the head which lies around the end of the cylinder, the cylinder head being formed of a metal having a coefficient of expansion different from that of the metal of which the cylinder is formed, and an annular member 95 mounted and fitting closely on the coned portion of the cylinder head spaced thereby wholly from the cylinder and formed of a metal having substantially the same coefficient of expansion as that of which the cylinder is formed.

5. In an air-cooled cylinder for internal combustion engines, the combination of an 100 open-ended cylinder, a cylinder head fitting on to and enclosing one end of the cylinder and having a coned surface and a screw-thread formed on that part of the head which lies around the end of the cylinder, the cylinder head being formed of a metal having a coefficient of expansion different from that of the metal of which the cylinder is formed, and an annular member internally 105 coned and screwthreaded and engaging the 110 metal having substantially the same coefficient of expansion as that of which the cylinder is formed.

6. In an air-cooled cylinder for internal combustion engines, the combination of an 115 open-ended cylinder, a cylinder head fitting on to and enclosing one end of the cylinder and having a coned surface and a screw-thread formed on that part of the head which lies around the end of the cylinder, the cylinder head being formed of a metal having a coefficient of expansion different from that of the metal of which the cylinder is formed, and an annular member internally 120 coned and screwthreaded and engaging the 125 metal having substantially the same coefficient of expansion as that of which the cylinder is formed.

coned and screwthreaded part of the head wholly spaced thereby from the cylinder and formed of a metal having substantially the same coefficient of expansion as that of which the cylinder is formed.

6. In an air-cooled cylinder for internal combustion engines, the combination of an open-ended cylinder, a cylinder head screwed on to one end of the cylinder and having a 10 coned surface and a screwthread formed on that part of the head which lies around the end of the cylinder, the cylinder head being formed of a metal having a coefficient of expansion different from that of the metal of which the cylinder is formed, and an annular member internally coned and screwthreaded and engaging the coned and screwthreaded part of the head spaced thereby wholly from the cylinder and formed of a 20 metal having substantially the same coefficient of expansion as that of which the cylinder is formed.

7. In an air-cooled cylinder for internal combustion engines, the combination of an 25 open-ended cylinder, a cylinder head fitting on to and enclosing one end of the cylinder and having separate coned and screwthreaded portions on that part of the cylinder head which lies around the end of the cylinder, the cylinder head being formed of a metal having a coefficient of expansion different from that of the metal of which the cylinder is formed, and an annular member screwthreaded internally and having a coned part 30 adapted to engage the coned part of the head when the annular member is screwed on to

the head, the annular member being completely spaced from the cylinder by the cylinder head and formed of a metal having substantially the same coefficient of expansion as that of which the cylinder is formed.

8. In an air-cooled cylinder for internal combustion engines, the combination of an open-ended cylinder, a cylinder head screwed on to one end of the cylinder and having a 40 separate coned and screwthreaded portions on that part of the cylinder head which lies around the end of the cylinder, the cylinder head being formed of a metal having a coefficient of expansion different from that of the metal of which the cylinder is formed and an annular member screwthreaded internally and having a coned part adapted to engage the coned part of the head when the annular member is screwed on to the head, 45 the annular member being formed of the same metal as the cylinder and completely spaced thereby from the cylinder head.

9. In an air-cooled cylinder for internal combustion engines, the combination of an 50 open-ended steel cylinder, an aluminium cylinder head screwed on to one end of the cylinder and having a coned surface and a screwthread formed on that part of the head which lies around the end of the cylinder, and an annular member formed of steel and 55 internally coned and screwthreaded to fit only on the coned and screwthreaded part of the head.

In testimony whereof I have signed my 70 name to this specification.

GEORGE SHAKESPEARE WILKINSON.
